US0D1024335S

(12) **United States Design Patent** (10) **Patent No.:** **US D1,024,335 S**
(45) **Date of Patent:** **** Apr. 23, 2024**

(54) **PERSONAL HEARING DEVICE**

(71) Applicant: **RELAJET TECH (TAIWAN) CO., LTD.**, Taipei (TW)

(72) Inventor: **Po-Ju Chen**, Taipei (TW)

(73) Assignee: **RELAJET TECH (TAIWAN) CO., LTD.**, Taipei (TW)

(**) Term: **15 Years**

(21) Appl. No.: **29/788,457**

(22) Filed: **Jun. 1, 2021**

(30) **Foreign Application Priority Data**

Dec. 1, 2020 (TW) 109306748

(51) **LOC (14) Cl.** **24-99**

(52) **U.S. Cl.**

USPC **D24/174**
